FLASK

Jose R. Perez Lias, Mexico City, Mexico

Application June 2, 1947, Serial No. 751,909
In Mexico June 22, 1946

3 Claims. (Cl. 215—6)

1

This invention relates to flasks, and particularly does it refer to a useful and novel flask making it possible to keep a given substance and its solvent separate, and to dissolve the former at the moment it is to be used.

The main object of the invention is to supply a flask provided with special means which will allow the user to preserve indefinitely a dry substance together with but out of contact with its solvent and makes it feasible for the solution to be made at a given moment, as for example, when it is dispensed, which is of great value where a freshly made solution is intended to be used.

The features of the invention will be apparent from the following description and from the accompanying drawings which serve as a typical illustration of a practical embodiment of the invention, the same reference characters being used to designate the same or like parts.

In the drawings:

Fig. 1 is an elevation of a flask made according to the invention, and

Fig. 2 is a vertical section of the same flask partly in elevation, for the purpose of better disclosing its features and inside arrangement.

Before describing this invention in a detailed manner as shown in the drawings, it is to be understood that the drawings merely show by way of example the preferred form of putting it into practice, and thus the invention is not restricted to the specified details as illustrated and described. Therefore, changes and modifications may be made without departing from the scope of the invention, or from the features thereof set forth hereinafter in the claims.

As will be understood from the foregoing, the flask embodying my invention allows a dry substance to be preserved together with, but out of contact with a liquid solvent and provides convenient means for preparing the solution at the moment when it is to be used or applied. According to the accompanying drawing, flask 10, which may be of the common or standard type, is provided with a cover or mantle 11, which is preferably threaded on to the neck 12 of the bottle or flask. This cover or mantle may be made of a plastic material, such as caoutchouc, etc. and will be open at the top 13, in order to admit a rod 14, which is normally supported within the flask. The lower end of the rod is hollow and provides an inverted glass or recess member 15, as will be more clearly noted by inspecting Fig. 2. The cover or mantle 11 is provided with a packing element 16 in its bore 13 for the admission of rod 14 and for providing an effective seal for the flask.

The flask provides at its bottom an upwardly extending integral element or projection 17 which is perfectly centered, the interior shoulder of inverted hollow glass container or recess member

2

15 at the lower end of rod 14 being fitted and adjusted thereto. An effective hermetic seal of the recess of inverted glass or container 15 may be secured by grinding the contact surfaces by means of wax, resin, or like packing material giving the same result. Member 17 is preferably frusto-conical and virtually forms a stationary closure for inverted container 15, which is of corresponding form but deeper than the height of member 17, so that an internal chamber results between the two.

The dry substance to be dissolved is kept within recess member 15 at the end of rod 14, and rests on the upper surface of upwardly projecting member 17, and if these parts are properly adjusted, the liquid or solvent may be enclosed within the flask, so that by removing rod 14, the liquid solvent may be instantly brought into direct contact with the dry substance to make the solution.

20 Following claims are made:

1. In a flask comprising a hollow flask body having an imperforate closed bottom, side walls and an opening in the upper end thereof, the combination of an integral upwardly extending projection forming a closure member upon the intermediate portion of the bottom within the flask body; and an insertible rod adapted to extend down into the latter and having a cavity in the lower end thereof forming a container on said rod of greater internal depth than the height of the projection or closure member upon said bottom and removably fitting said projection or closure member tightly so that an internal chamber results between the upper end of said projection and the inner end or bottom of said cavity or container.

2. In a flask comprising a hollow flask body having an imperforate closed bottom, side walls and an opening in the upper end thereof, the combination of an integral upwardly extending frusto-conical projection forming a closure member upon the intermediate portion of the bottom within the flask body; and an insertible rod adapted to extend down into the latter and having a corresponding tapered cavity in the lower end thereof forming a container on said rod of greater internal depth than the height of the projection or closure member upon said bottom and removably fitting said projection or closure member tightly so that an internal chamber results between the upper end of said projection and the inner end or bottom of said cavity or container.

3. In a flask comprising a hollow flask body having an imperforate closed bottom, side walls and an opening in the upper end thereof, the combination of an integral upwardly extending frusto-conical solid projection forming a closure member upon the intermediate portion of the bottom within the flask body; and an insertible

rod adapted to extend down into the latter and having a corresponding inwardly or upwardly tapered cavity in the lower end thereof forming a container on said rod of greater internal depth than the height of the projection or closure member upon said bottom and removably fitting said projection or closure member tightly so that an internal chamber results between the upper end of said projection and the inner end or bottom of said cavity or container.
